UNITED STATES PATENT OFFICE

PAUL STORCH, OF BERLIN-CHARLOTTENBURG, GERMANY, ASSIGNOR TO SIEMENS & HALSKE, AKTIENGESELLSCHAFT, OF SIEMENSSTADT, NEAR BERLIN, GERMANY, A CORPORATION OF GERMANY

CHEMICAL PICTURE-TELEGRAPH EQUIPMENT

Application filed October 30, 1930, Serial No. 492,192, and in Germany September 20, 1929.

Chemical picture-telegraph equipments are mostly in need of a moistening device for the picture support which consists of paper with a chemical preparation or emulsion thereon. 5 For moistening the paper according to the prior art, it has been customary to pull the paper prior to use by hand through a dish containing liquid, or else, if the paper was fed from a storage spool, the paper was automatically passed underneath a roller through the liquid as the paper was fed forward. It has also been suggested to guide the paper over a split tube which was in connection with a liquid-container. But in all of these 10 devices the paper becomes moistened either irregularly or unduly, with the result that the signal, pictures or the like to be transmitted become blurred, and that also a blurred picture is reproduced. 15 The present invention aims to eliminate this drawback by guiding the picture carrier or support over a roller, spool, or equivalent device adapted to spread the moistening liquid. In this arrangement, the roller may move inside the liquid over part of its circumference and thereby supply an always constant and properly proportioned volume of liquid to the support guided over another 20 part of the circumference. 25 Another improvement may be obtained by covering the surface of the roller with a porous absorptive material such as burned or baked clay. Another embodiment would be to store the liquid in the interior of the roller and provide perforations for the outflow of the liquid towards the roller surface. In this scheme it is also desirable to cover the surface of the roller with a cylinder consisting of 30 baked clay in order to thus prevent the paper from being moistened more strongly in some places than in others.

The principle of the invention is illustrated by the accompanying drawing wherein Figs. 45 1-3 illustrate various embodiments of the

basic idea of the invention by way of example.

Referring now to the drawing, inside the drum-like vessel 1 having a fairly wide slit there moves the rotatably supported roller or cylinder 2, part of whose circumference dips into the liquid 3. The strip or tape of paper 6 which is reeled off from the storage spool 4 is pressed against the cylinder 2 by the presser roll 5 and is then guided over the inker blade 7. Opposite the inking blade or edge 6 is the recorder electrode 12 which is in contact engagement with the paper 6. 50

The paper is here preferably moistened from the rear. The roll 2 becomes moistened 60 uniformly with the liquid so that it will also moisten uniformly the paper coming in contact therewith.

In the embodiment shown by way of example in Fig. 2, the roller or cylinder 8 consists at least superficially of an absorbent material, say, porous clay. The strip of paper 6 is here conducted preferably over a relatively large circumference of the roller, the time of contact and thus the degree of moistening in each instance being exactly measurable or controllable by also making the rolls 9 and 10 adjustable. 65

Fig. 3 shows an embodiment in which the liquid is located in the interior of the cylinder 75 the inner shell 11 of which consists of impermeable material having perforations 13. Over the said shell 11 is a layer of porous material 14, say, clay and hemp, felt, or the like, so that the liquid exuding through the 80 openings 13 is able to become uniformly distributed over the coat of clay and thus be imparted to the paper 6.

Other modifications and changes may suggest themselves to those skilled in the art to 85 which the invention relates, and I, therefore, believe myself to be entitled to make and use any and all of such modifications as fall fairly within the spirit and scope of the hereinafter appended claim. 90

Having now described my invention, what I claim and desire to secure by Letters Patent is the following:

In an apparatus for receiving pictures on moistened chemical records, a container roll having a filling of chemical moistening material therein, a porous absorptive material on the periphery of said container, means for moistening said material with the liquid contained within said container, and means for 5 passing a record strip over approximately half of the periphery of said container roll in contact with said material, whereby the record strip is moistened by the chemical solution.

10 15 In testimony whereof I affix my signature.

PAUL STORCH.
